ASH TRAY

Vincent S. Belpedio, Fairfield, and George L. Barton, Bridgeport, Conn.

Application July 29, 1952, Serial No. 20,808

Term of patent 14 years

(Cl. D85—2)

To all whom it may concern:

Be it known that we, Vincent S. Belpedio and George L. Barton, citizens of the United States and residents, respectively, of Fairfield, Connecticut, and Bridgeport, Connecticut, have invented a new, original, and ornamental Design for an Ash Tray, of which the following is a specification, reference being had to the accompanying drawings, forming part thereof.

In the drawings:

Fig. 1 is a perspective view of the ash tray, showing our new design;
Fig. 2 is a plan view;
Fig. 3 is a side elevation;
Fig. 4 is a sectional view, taken along the line 4—4 of Fig. 2;
Fig. 5 is an end elevation; and
Fig. 6 is a sectional view, taken along the line 6—6 of Fig. 2.

We claim:

The ornamental design for an ash tray, substantially as shown.

VINCENT S. BELPEDIO.
GEORGE L. BARTON.
